UNITED STATES PATENT OFFICE.

CHARLES L. COOKSON, OF KANSAS CITY, MISSOURI.

EXPLOSIVE-ENGINE.

1,110,612.

Specification of Letters Patent. Patented Sept. 15, 1914.

Application filed October 30, 1909. Serial No. 525,544.

To all whom it may concern:

Be it known that I, CHARLES L. COOKSON, a citizen of the United States, residing at Kansas City, in the county of Jackson and 5 State of Missouri, have invented certain new and useful Improvements in Explosive-Engines, of which the following is a specification.

This invention relates to explosive engines 10 and more especially to engines of the four cycle rotating-valve type and my object is to produce an engine of this character that will be efficient, reliable and practically noiseless in operation.

15 A further object is to produce an engine having a rotary or balance valve through which the explosive mixture is supplied to the cylinder and the exploded mixture is withdrawn from the cylinder and which is 20 geared to and operated from the crank shaft of the engine.

A still further object is to produce an auxiliary exhaust for cylinders to permit 25 flame and heat to escape and thus eliminate in a large measure the production of carbon on the valve and the consequent necessity at frequent intervals of removing and planing the valve.

With these objects in view and others as 30 hereinafter appear, the invention consists in certain novel and peculiar features of construction and organization as hereinafter described and claimed; and in order that it may be fully understood reference is to be 35 had to the accompanying drawings, in which:

Figure 1, is a side elevation of a four cylinder engine embodying my invention. Fig. 2, is a horizontal section on the line II—II 40 of Fig. 1. Fig. 3, is an enlarged vertical section on the line III—III of Fig. 4. Fig. 4, is a horizontal section on the line IV—IV of Fig. 3. Fig. 5, is a horizontal section on the line V—V of Fig. 3. Fig. 6, is a detail 45 perspective view of the crank shaft and pistons of the engine. Fig. 7, is a detail perspective view of one of the combined inlet and exhaust valves employed in duplicate in a four cylinder engine.

50 In the said drawings, where like reference characters identify corresponding parts, 1 indicates the crank case and 2, 3, 4 and 5 the cylinders superposed with respect to and communicating at their lower ends with the 55 crank case. Each cylinder is provided with one or more auxiliary exhaust ports 6

communicating with a manifold exhaust chamber 7, and communicating with the upper end of said cylinder through the head thereof, is a spark plug 8 60 of an electrical igniter, though it is to be understood that the ignition apparatus may be of any other or well known type. Each pair of cylinders 2 and 3, and 4 and 5 are also provided at their upper or head ends 65 with intake ports 9 and exhaust ports 10 communicating respectively with intake and exhaust openings 11 and 12 of the inverted frustum-shaped lining 13 of the valve casing 14 cast integral by preference, with the 70 cylinders, and communicating with the interior of each lining at its lower end is a tubular arm 15, said arms receiving the charges of explosive mixture for their respective cylinders, through the manifold or 75 branched intake pipe 16 leading from the carburetor, not shown. The upper end of each valve casing 14 is closed by a cap 17, which caps are connected by a manifold or branched exhaust pipe 18, to the manifold 80 exhaust chamber 7, as shown clearly in Fig. 1, the opposite ends of said manifold or branched pipe communicating through the caps 17 with the interior of the linings 13 at the upper ends of the same. 85

19 indicates an inverted frustum-shaped valve for and fitting snugly and with a gas-tight relation in each lining 13, and said valve is divided by a horizontal partition 20 into a lower or intake chamber 21 communicating with the underlying arm 15, and an upper or exhaust chamber 22 communicating with the exhaust manifold pipe 18. 90

Each valve is provided with an intake port 23 for establishing communication once 95 in each revolution between chamber 21 of the valve and the ports 9 of the associated pair of cylinders, and with exhaust port 24 for establishing communication once in each revolution of the valve, between exhaust 100 chamber 22 thereof and the exhaust ports 10 of said associated cylinders, and to coöperate in centralizing the valve in its lining and insure perfect rotation, each valve is provided with an upwardly-projecting tubular extension 25 fitting snugly in the overlying cap 17. 105

The partition 20 of the valve is provided with a socket 26 in its underside to nonrotatively receive the head 27 of a vertical 110 shaft 28 extending down through the arm 15 and bearing a journaled and gas-tight rela-

tion thereto. Said shaft is coupled as at 29 or otherwise to the upper end of an alined shaft 30 extending down into the crank case and equipped at its lower end with a miter gear 31; said coupling permitting of easy and quick rotative adjustment of the valve, when necessary. Shaft or shaft member 30 as said shafts 28 and 30 are practically one, is provided with a thread 32 engaged by 10 lock-nuts 33, and a ball bearing 34, is interposed between the lock-nuts and the crank case to reduce friction to the minimum.

By means of the lock-nuts the valve can 15 be prevented from settling in its lining to such an extent as to develop unnecessary friction. The miter gear 31 meshes with a similar gear 35 upon shaft 36 equipped with a large gear wheel 37 meshing with a smaller 20 gear wheel 38 on the crank shaft 39; said shaft being provided in a four cylinder engine, with cranks 40 and 41, and 42 and 43. 25 44 indicate piston stems connecting said cranks with the pistons 45 arranged to reciprocate in the cylinders in the customary manner.

Each pair of cylinders and its associated valve casing is enveloped in a water-jacket 46, a water-supply pipe 47 being connected 30 to the lower end of each water-jacket and a discharge pipe 48 to the upper end of each jacket. To lubricate each valve, it is provided with a longitudinal groove 49, in communication once in each revolution with a 35 passage 50 constantly supplied with oil by a pipe 51, this arrangement insuring the proper lubrication of the valve.

Referring now to the operation of one of the pistons, viz., the piston of cylinder 2, 40 and the valve associated therewith, it will be assumed that the piston is at the upward-limit of its compression stroke and is about to move downward under ignition and that openings 11 and 12 are closed by the valve. 45 At this instant a spark is produced by the ignition mechanism and under the force of the explosion the piston is impelled downward, the valve rotating a quarter revolution at the same time because the ratio of 50 movement between the crank shaft and shaft 36 is two to one. As the piston attains its most depressed position a large proportion of the flame and heat escapes through the port 6 of the cylinder into the manifold exhaust chamber 7. Shortly after the up or 55 exhaust stroke of the piston starts, viz., after the piston has reclosed port 6, the exhaust port 24 of the valve comes into communication with opening 12 and port 10 to permit the piston in such upstroke to expel or scavenge the dead gases from the cylinder through port 10, opening 12, chamber 22 of the valve and exhaust pipe 18 to the manifold exhaust chamber 7.

60 As the piston starts on its second down-

stroke, which is the suction stroke, the exhaust port 24 passes out of communication with opening 12, and intake port 23 of the valve comes into communication with opening 11 and port 9 and as a result the cylinder is charged above the piston with the requisite volume of explosive mixture. As the piston starts on its second up-stroke, viz., the compression stroke, the rotation of the valve has carried port 23 out of communication with opening 11 and port 9, and as a result of such up-stroke of the piston and the closure of opening 11 by the valve, the explosive mixture is compressed and ready to be fired at the completion of said up-stroke of the piston, the succeeding operations being repetitions of the one cycle of operations described.

In Fig. 6, the four pistons occupy the four different positions which each piston assumes in one complete cycle of operation, that is to say the piston connected to crank 40 is in the position it occupies when ignition takes place, the piston connected to crank 42 is in the depressed position which it occupied preliminary to making its up or exhaust stroke, the piston connected to crank 43 is in the elevated position which it occupies preliminary to the suction stroke and the piston connected to crank 41 is in the depressed position it occupied preliminary to the compression stroke, and below each of said pistons is a diagram illustrative of the four movements of such pistons, and their preferred relation to each other, that is to say, when the piston connected to crank 40 is making its down stroke on ignition, the piston connected to crank 43 is making its down stroke on suction, the pistons connected to cranks 42 and 41 at the same time making their up-strokes respectively on exhaust and compression, the diagrams indicating clearly the relative actions of the pistons in all of their strokes.

Where the ratio of operation between the 110 crank shaft and the valve-operating shaft 26, is two to one as explained and a single valve is associated with a pair of cylinders, it will be understood that the intake port 23 alternately communicates with the openings 11 in communication through the ports 9 with their respective cylinders, and that of course is true of the exhaust port 24. With the crank shaft and piston operating in the ratio of two to one, and the openings 115 11 and 12 disposed in the same vertical plane, as shown, it is necessary that ports 23 and 24 shall be disposed in different vertical planes a distance apart about equal to one-eighth of the circumference of the valve, 120 the relative positions of the ports of the latter and one of the pistons being traced as follows: As port 23 registers with openings 11, piston 45 moves downward in its 125 suction stroke. As this stroke is ended open-

ing 11 is closed through the movement of the valve, and remains closed as does opening 12 until the piston has completed its up or compression stroke, by which time the valve has 5 turned one-half revolution and the crank shaft a full revolution. The compressed mixture is then exploded and the piston is forced downward by the power thus generated and as it makes such second down- 10 stroke the valve completes an additional or third one-quarter revolution. As the piston starts upward the second time, such second up-stroke being the exhaust stroke, port 24 comes into communication with opening 12 15 to permit the dead gases to be expelled from the cylinder, and as said piston stroke is completed the port 24 passes out of engagement with opening 12, at which time, the crank shaft has made a second full revolution 20 so that at the beginning of the second cycle of movement of the piston, the intake port of the valve will again pass into communication with port 11, as will be readily understood. It will be apparent of course 25 that the openings 11 and 12 may be disposed in different vertical planes and the openings in the valve in the same vertical plane, and that by multiplying the ratio of movement between the crank shaft and valve-operat- 30 ing shaft, it will be necessary to likewise multiply the ports 23 and 24 in order that the explosive mixture may be supplied to and the dead gases be expelled from the cylinders at the proper time.

35 From the above description it will be apparent that I have produced an explosive engine which will operate efficiently and reliably and without the noise or clatter incident to the use of reciprocatory or other 40 valves which alternately strike against and move away from their seats. It will also be apparent that by providing for the escape of flame through port or ports 6, the deposit of carbon on the valve will be reduced to a 45 minimum and hence it will be seldom necessary to remove and grind the valve. It will also be apparent that the engine embodies

other features of advantage enumerated as desirable in the statement of the object of the invention and that it is susceptible of 50 modification in various particulars without departing from the essential spirit and scope of the appended claim.

Having thus described the invention what I claim as new and desire to secure by Letters-Patent, is:

The combination with a plurality of cylinders, each having an inlet port and an exhaust port, of a single valve casing having a plurality of ports registering severally 60 with each of the cylinder ports, a single rotary valve operating within said casing, a transverse partition dividing said valve into an inlet and an exhaust chamber, said valve being provided with axial openings and said 65 casing also having inlet and outlet openings in constant communication respectively with said valve openings, the inlet chamber of said valve being provided with a port adapted to register once in each revolution with 70 each of the ports of the valve casing that register with the inlet ports of said cylinders for successively supplying an explosive mixture thereto, and the exhaust chamber of said valve being provided with a port 75 adapted to register once in each revolution with each of the ports of the valve casing that register with the exhaust ports of said cylinders for successively receiving the exhaust from said cylinders, said partition being provided centrally of one of its faces 80 with an angular socket and a valve operating shaft extending axially of the valve through one of said casing openings and the corresponding valve opening into the valve 85 chamber on the socketed side of said partition, said shaft having an angular head fitting snugly into said socket.

In testimony whereof I affix my signature in the presence of two witnesses,

CHARLES L. COOKSON.
